[57] CLAIM

The ornamental design for a combined vehicle window scraper and brush, as shown and described.

DESCRIPTION

FIG. 1 is a top, right side, and front perspective view of a combined vehicle window scraper and brush showing my new design;

FIG. 2 is a right side elevational view;

FIG. 3 is a top plan view;

FIG. 4 is a rear elevational view;

FIG. 5 is a front elevational view thereof; and,

FIG. 6 is a bottom elevational view thereof; The left side elevational view is a mirror image of the side shown in FIG. 2.
